INSULATED ICE CHEST OR SIMILAR ARTICLE

Harvey Hanig, North Aurora, Ill., and Donald P. Mastrovito, Shrewsbury, Mass., assignors to Standard Oil Company, Chicago, Ill.

Filed Feb. 18, 1971, Ser. No. 116,736

Term of patent 14 years

Int. Cl. D7—99

U.S. Cl. D44—1

FIG. 1

FIG. 2

FIG. 3

FIG. 4

FIG. 5

FIG. 6

FIG. 1 is a perspective view of an insulated ice chest or similar article showing our new design;

FIG. 2 is a top plan view;

FIG. 3 is a bottom plan view;

FIG. 4 is a front elevational view;

FIG. 5 is a side elevational view; and

FIG. 6 is a rear elevational view.

The surface pattern fragmentarily shown in FIGS. 1 and 2 is continuous over the top surface of the insulated ice chest or similar article.

We claim:

The ornamental design for an insulated ice chest or similar article, as shown and described.
